FIG. 3

FIG. 1 is a perspective view of a camper trailer embodying my new design.

FIG. 2 is a side elevational view thereof partially in section the opposite side being a mirror image of the side shown herein; and

FIG. 3 is an end elevational view thereof.

The characteristic feature of my design resides in the specific configuration of the ends of the camper trailer, wherein the screened end windows are vertically arranged with a canvas roof overhanging each end window.

The fragmentary criss-cross patterns shown in the drawing are representative of screening and are understood to continue uniformly throughout the areas shown.
